FILE GUIDE

Eva L. Lee, Hamilton, Ohio

Application May 12, 1949, Serial No. 92,785

3 Claims. (Cl. 129—16.7)

1

This invention relates to guides for filing drawers used to separate groups of sheet material in the drawer and more particularly to a novel means for detachably securing such guides to the usual guide holding rod in such filing drawers.

The usual file drawer carries a rod which runs through the drawer front fore and aft of the drawer adjacent the drawer bottom and upon which the conventional guides or indexing separators are threaded through a grommeted aperture adjacent the lower edge of the guide. This guide rod is secured both at its front and rear ends in the drawer so that in order to remove a guide the rod must first be released and then drawn through the guide to be removed.

Filing procedure often requires that one or more guides be moved from one location in a file drawer to another in that drawer or moved from one drawer to another drawer. Heretofore this procedure has required withdrawing the guide rod not only from the guides to be moved but also from those which are to remain in their original places and then re-threading the rod through all guides after the changes have been made. During this file drawer rearrangement it is almost impossible to hold the remaining guides in their original positions and to reinsert the shifted guides so that their rod threading apertures are aligned for easy reinsertion of the rod, and much time is lost in "hunting" for the aperture in each guide as the rod is reinserted.

It is an object of this invention, therefore, to provide a guide for a file drawer of the type having a guide rod which may readily and easily be removed from the rod or reinserted thereon without the necessity of first removing the rod or removing other guides from the rod, but which will be securely held on the rod against accidental removal.

Another object of the invention is to provide a guide of the above character provided with an inverted L-shaped or bayonet slot in which the guide rod is removably held, the arrangement and position of the slot being such that removal of the guide from the rod is inhibited so long as the guide occupies its normal flat position transversely straight across the drawer but permits easy withdrawal from the rod by bending or twisting the guide about a vertical axis so that the guide may be shifted transversely an abnormal amount.

Another object of the invention is to provide a guide of the above character in which the guide body is formed of cardboard or the like in a substantially rigid, flexible sheet and the wear resistant tab rigidly secured to each sheet.

2

A further object of the invention is to provide a file guide of the above character which is economical to manufacture in a wide variety of sizes and from a wide variety of materials.

5 With the above and other important objects and advantages in view, which will become more apparent during the course of the following description, the invention consists in the parts and combinations hereinafter set forth with the 10 understanding that various changes may be made therein by those skilled in the art, such as in the size, shape, and arrangement of the parts and by the substitution of equivalents and materials, without departing from the spirit of the invention 15 or exceeding the scope of the appended claims.

In order to make the invention more clearly understood, a preferred embodiment thereof has been made the subject of illustration in the accompanying drawings in which:

20 Figure 1 is a view in front elevation of a file guide, according to the invention, showing its position in a file drawer, the drawer being shown somewhat conventionally in transverse section;

25 Figure 2 is a horizontal cross sectional view taken along the line 2—2 of Figure 1 looking in the direction of the arrows and showing the guide in its normal position;

Figure 3 is a view similar to Figure 2 but showing the guide flexed about a vertical axis and shifted transversely to one side to a position 30 where it can be removed from the guide rod; and

Figure 4 is a vertical cross sectional view taken along the line 4—4 of Figure 1 looking in the direction of the arrows.

Referring more particularly to the drawings, 35 my file guide comprises a rectangular sheet 1 which preferably and economically may be composed of fiber board, cardboard or other suitable flexible and resilient sheet material which will retain its shape under normal usage. The upper edge of the sheet 1 may be formed with the usual upwardly extending index tab 2. The sheet 1 may be made in various sizes according to the particular filing equipment in which it is to be used, for example correspondence files, legal files, 40 and the various sizes of card index files.

Secured to the lower edge 3 of the sheet 1, intermediate its vertical edges 4, is a rod engaging tab 5. In its preferred form, the tab 5 is formed from a relatively thin strip of metal 6, such as 45 sheet steel or brass, which is folded upon itself intermediate its length, as shown in Figure 4. The free ends 7 of the strip straddle the lower edge of the sheet 1 and are riveted together through the sheet, as indicated at 8. While the 50 above mentioned material and method of form-

55

ing and attaching the tab 5 are preferred, it is obvious that the tab could be made from a single ply of metal, relatively stiff sheet plastic, or other suitable wear resisting material, and otherwise suitably attached to the sheet. Alternately, 5 the tab 5 could simply be formed directly on the sheet 1 when it is cut.

Formed in the tab 5 is an inverted L-shaped or bayonet slot 8 having a vertical portion 10 opening on the bottom edge of the tab, and a horizontal portion 11 extending laterally from the upper end of the vertical portion and communicating therewith. The extremity of the horizontal portion of the slot 8 is closed and the lower edge of the horizontal portion is formed with a slight downward extension or depression which constitutes a rod receptor 12 and forms a slight ridge 13 adjacent the juncture of the horizontal and vertical portions of the slot. It will be noted in Figure 1 that the minimum width 20 of the slot 8 is sufficient to freely receive a guide rod, indicated generally as 14, and that the rod receptor 12 lies substantially in the vertical center line of the sheet 1.

It will be seen also in Figure 1 that the width 25 of the sheet 1 is such as to provide a slight clearance between the vertical edges 4 of the sheet and the adjacent side walls 15 of a file drawer 16. The length of the horizontal portion of the slot 8, on the other hand, from the center of the receptor 12 to the center of the vertical portion 10 is greater than the combined spaces between the vertical edges of the sheet 1 and the side walls of the drawer so that the rod 14, when in the horizontal portion of the slot, as will be described, cannot register with the vertical portion 10 in any transversely shifted position of the guide so long as the sheet 1 is in its normal flat condition and extending transversely straight across the drawer. On the other hand, it will be seen that if the sheet 1 is flexed or otherwise displaced about a vertical axis so as to increase the clearance between a vertical edge 4 and the adjacent side wall of the drawer, the guide may be shifted transversely further and the open vertical portion of the slot 8 brought into registration with the rod 14, and the tab 5 can be engaged or disengaged freely from the rod.

In operation, when it is desired to insert a guide in a file drawer, the sheet 1 is grasped in its upper portion near opposite edges and flexed or bent slightly about a vertical axis as shown in Figure 3 (or it may simply be held flat at an angle to one of the side walls of the drawer) and the guide is lowered vertically in the drawer. When the tab 5 strikes the rod 14, the guide is shifted to the left (as seen in Figure 1) until the rod enters the open vertical portion 10 of the slot 8. When the rod engages the upper edge of the horizontal portion of the slot, the guide is straightened out and shifted laterally to the right to bring the rod through the horizontal portion of the slot and into the receptor 12. The natural resiliency of the sheet 1 maintains it in a flat condition and when it is in normal use in a file, it extends straight across the drawer being aligned by the filed material between the guides and the drawer front and usual follower. In this position, therefore, it cannot shift transversely enough to bring the vertical portion of the slot into registration with the rod 14 and the guide will be securely held on the rod against accidental removal.

When the rod is in the receptor 12, the increased depth of the receptor affords a substan-

tial clearance between the upper and lower edges of the horizontal position of the slot and permits an ample front and back angular movement of the guide on the rod for fanning the guides and easy inspection or insertion and removal of the filed material.

When it is desired to remove a guide, the same procedure is followed. The guide is grasped and bent as above described and then shifted transversely until the rod engages the edge of the vertical slot away from the closed end of the horizontal slot. The guide may now simply be lifted off the rod and out of the drawer.

From the foregoing it will be seen that the invention provides a file guide which may readily and easily be inserted and removed from engagement with a guide rod in a file drawer without the necessity of removing the rod from its fastening in the drawer and without disturbing other guides in the drawer. The guide and its means for holding in the drawer are of economical but rugged construction and may be subjected to long usage without substantial wear or damage. While only a preferred embodiment has been shown by way of illustration, it will be appreciated that it may be modified in size and shape and material to adapt it to the particular filing equipment in which it is to be used. For example, the guide rod in most files is below the main bottom of the drawer and the depending tab 5 is required on the guide to reach the rod. In certain card files, however, the rod may be above the drawer bottom, in which case the inverted L-shaped slot 8 may be formed in the sheet 1 itself and suitably reinforced to withstand wear.

I claim:

1. In a file drawer of the type described having side walls, a bottom, a longitudinal channel in the bottom, and a rod extending fore and aft in the channel in the bottom of the drawer, the improvement comprising a flexible rectangular guide adapted to be positioned generally upright in the drawer and extending transversely thereof between the side walls, a tab of substantially rigid wear-resistant material secured to the lower edge of the guide and positioned to extend into the channel, said tab having therein a generally inverted L-shaped slot adapted to receive the rod, the slot being positioned in the portion of the tab extending beneath the guide sheet, said slot having a downwardly opening vertical portion and a closed horizontal portion extending therefrom and communicating therewith, the rod being normally positioned in the horizontal portion of said slot, the length of the horizontal portion of the slot being greater than the space between the vertical edge of the guide sheet toward which the horizontal portion of the slot extends and the side of the drawer, the width of the tab being less than the width of the channel by at least the length of the horizontal portion of the slot to permit transverse movement of the guide in the drawer to align the vertical portion of the slot with the rod, and the position of said vertical portion of the slot with respect to the vertical edges of the guide sheet and the position of the rod, and the width of the guide sheet with respect to the width of the drawer, being such that in all positions of the guide in a flat condition normal to the side walls said vertical portion of the slot will be out of registration with the rod.

2. In a file drawer of the type described having side walls, a bottom, a longitudinal channel in the bottom, and a rod extending fore and aft in the

channel in the bottom of the drawer, the improvement comprising a flexible rectangular guide adapted to be positioned generally upright in the drawer and extending transversely thereof between the side walls, a tab of substantially rigid wear-resistant material secured to the lower edge of the guide and positioned to extend into the channel, said tab having therein a generally inverted L-shaped slot adapted to receive the rod, the slot being positioned in the portion of the tab extending beneath the guide sheet, said slot having a downwardly opening vertical portion and a closed horizontal portion extending therefrom and communicating therewith, the rod being normally positioned in the horizontal portion of said slot, a horizontal edge of the horizontal portion of the slot being curved whereby the width of said horizontal portion of the slot is greatest substantially at its center, the length of the horizontal portion of the slot being greater than the space between the vertical edge of the guide sheet toward which the horizontal portion of the slot extends and the side of the drawer, the width of the tab being less than the width of the channel by at least the length of the horizontal portion of the slot to permit transverse movement of the guide in the drawer to align the vertical portion of the slot with the rod, and the position of said vertical portion of the slot with respect to the vertical edges of the guide sheet and the position of the rod, and the width of the guide sheet with respect to the width of the drawer, being such that in all positions of the guide in a flat condition normal to the side walls said vertical portion of the slot will be out of registration with the rod.

3. In a file drawer of the type described having side walls, a bottom, a longitudinal channel in the bottom, and a rod extending fore and aft in the channel in the bottom of the drawer, the improvement comprising a flexible rectangular guide adapted to be positioned generally upright in the drawer and extending transversely thereof between the side walls, a tab of substantially rigid wear-resistant material folded back upon it-

self and straddling the lower portion of the guide, means clamping the tab in folded position and securing the tab to the guide, said tab being positioned to extend into the channel, said tab having therein a generally inverted L-shaped slot adapted to receive the rod, the slot being positioned in the portion of the tab extending beneath the guide sheet, said slot having a downwardly opening vertical portion and a closed horizontal portion extending therefrom and communicating therewith, the rod being normally positioned in the horizontal portion of said slot, the length of the horizontal portion of the slot being greater than the space between the vertical edge of the guide sheet toward which the horizontal portion of the slot extends and the side of the drawer, the width of the tab being less than the width of the channel by at least the length of the horizontal portion of the slot to permit transverse movement of the guide in the drawer to align the vertical portion of the slot with the rod, and the position of said vertical portion of the slot with respect to the vertical edges of the guide sheet and the position of the rod, and the width of the guide sheet with respect to the width of the drawer, being such that in all positions of the guide in a flat condition normal to the side walls said vertical portion of the slot will be out of registration with the rod.
